(57) **CLAIM**

The ornamental design for container for pharmaceutical tablets, as shown and described.

DESCRIPTION

FIG. 1 is a perspective view of a container for pharmaceutical tablets, as shown from the top left, showing my new design;

FIG. 2 is a top plan view thereof;

FIG. 3 is a right-hand elevational view thereof;

FIG. 4 is a left-hand elevational view thereof;

FIG. 5 is a bottom plan view thereof;

FIG. 6 is a front elevational view thereof, the rear elevational view being a mirror image thereof; and,

FIG. 7 is a perspective view similar to FIG. 1, showing the container in the open position.

1 Claim, 4 Drawing Sheets
